CHARLES L. COLLINS AND JAMES V. ANZULOVIC, OF OMAHA, NEBRASKA

ADJUSTABLE SLICING MACHINE

Application filed January 3, 1930. Serial No. 418,339.

This invention relates to adjustable slicing machines and is particularly adapted for slicing circular ice cream bars.

An object of the invention is to provide a slicing machine of the character referred to, the length of the slices of which may be regulated to any determined size with ease and dispatch.

Further objects of the invention are to provide a slicing machine of the character referred to that is very pleasing in appearance, strong, compact and durable, relatively light in construction, very sanitary, very simple in its method of assembly, and comparatively inexpensive to manufacture and operate.

With the foregoing and other objects in view, the invention consists of a novel construction, combination and arrangement of parts as will be hereinafter more specifically described and illustrated in the accompanying drawings, wherein is disclosed an embodiment of the invention, but it is to be understood that changes, variations and modifications may be resorted to without departing from the spirit of the invention as claimed.

In the drawings wherein like reference characters denote corresponding parts throughout the several views:

Figure 1 is a top plan view of the slicing machine in accordance with the present invention.

Figure 2 is an end elevation thereof.

Figure 3 is a fragmentary vertical section in detail taken substantially on line 3—3 of Figure 1.

Figure 4 is an enlarged fragmentary plan view of a portion of the spindle illustrating the method of mounting the slicing blade thereon.

Figure 5 is a detailed section taken substantially on line 5—5 of Figure 8.

Figure 6 is a plan view of the knife blade.

Figure 7 is a side elevation of the knife blade.

Figure 8 is a fragmentary detailed section taken substantially on line 8—8 of Figure 1.

Referring to the drawings in detail, 10 indicates the base of the slicer which is relatively rectangular in configuration and having a flat bottom. The upper face of the base

10 is flat for one-half its width, as indicated at 11. The base 10 is further formed with an upstanding rib 12 adjacent one side thereof. The upstanding rib 12 is above the level of the flat portion 11 of the base, and between the upstanding rib and the flat face there is an arcuate depression 13 extending longitudinally throughout the entire length of the base. 55

Intermediate the ends of the depression 13 there is a counter-sunk groove 14 V-shaped in cross section. At the ends of the base 10 are a pair of transversely disposed, upstanding supporting plates 15, 16, that are supported on the flat face of the base 10. A circular 60 spindle 17 has the opposite ends thereof supported in openings 18 in the supporting plates 15, 16, and the spindle 17 is prevented from turning by a set screw 19 threaded through an opening 20 in the support 16, the 65 inner end of which merges with the opening 18. 70

The inner end of the set screw 19 is pointed and is sufficiently hard to bight into the spindle 17 so as to obtain a firm grip thereon to prevent the turning of the spindle. The spindle 17 extends longitudinally of the base 10, in spaced relation to the upper flat face 11. 75

An upstanding supporting brace 21 is secured to the side edges of the base 10 adjacent the flat face 11 and projecting inwardly therefrom are a pair of longitudinally spaced ears 22, 23, that serve to strip the ice cream or other articles being sliced from the knife blade to be presently described. 80

The knife is indicated generally at 24 and is formed with a handle 25 at one end and an elongated sleeve 26 at the other end projecting laterally from the handle and intermediate the sleeve and the handle the knife is 85 formed with an arcuate blade receiving shank 27. One side face of the shank 27 is recessed at 28 and intermediate the ends of the recess there is an outset lug 29. Seated in the recess is the knife blade 30 having a slot 31 90 therein that fits about the lug 29 to provide additional support to prevent the blade from slipping. 95

The blade is further secured in the recessed shank by a pair of screws 32. The free edge 100

of the blade is curved and bevelled as at 33 to provide a knife edge for cutting articles such as ice cream or the like. The knife 24 is rotatably mounted on the spindle 17 by having the sleeve 26 circumposed thereabout. The handle 25 and the blade 30 are disposed between the ears 22, 23 and the bevelled edge 33 is in alinement with the groove 14 in the depression 13.

10 The sleeve 26 disposed on the spindle 27 projects toward the support 15 and has disposed thereabout a tensioned coil spring 34, one end of which terminates in a prong 35 that is anchored in an opening in a ring collar 36 rigidly secured to the spindle 17 by a set screw 37. The opposite end of the coil spring 34 is formed with a U-shaped hook 35' that overlaps the shank of the knife 24 adjacent the sleeve 26.

20 Keyed to the spindle 17 is a collar 36' that abuts the base of the shank of the knife adjacent the sleeve 26 so as to prevent the spring 34 from moving the knife out of alinement with the groove 14. The spring 34 exerts a twisting pressure upon the knife 24 so that the handle will normally be urged to a vertical position and the knife edge 33 free of the groove 14.

Beginning at the side margins, the upper 30 face of the support 16 is provided with a plurality of transversely spaced U-shaped pockets 37 and detachably secured over the upper face of the support is a cover plate 38 secured to the support by means of screws 39. 35 The cover plate closes the upper ends of the pockets 37 and extending through the cover plate, one in communication with each pocket are a plurality of threaded openings 40. In each of the openings there is threadably supported screws 41 the inner ends of which extend into the pockets 37.

45 A relatively elongated U-shaped guide yoke indicated generally at 42 projects inwardly from the end support 16 in spaced relation above the spindle 17. The legs of the yoke 43, 44 are square in cross section and are seated in the end pockets of the series of pockets 37. The end screws of the series 41 rigidly couple the ends of the legs of the yoke 42 in the pockets. A plurality of gauge fingers 45 are slidable in the other pockets 37 of the series and selectively adjustable in rigid relation to the support 16 by means of the screws 41.

55 The gauge fingers 45 are square in cross section and may be of unequal length as the purpose requires. The fingers 45 are disposed in the same horizontal plane as the legs of the yoke 43, 44. The gauge fingers are 60 transversely spaced from each other and lie within the yoke 42, the inner ends of which may be adjusted as desired.

An arcuate abutment plate 46 projects laterally from, and is secured to a portion of the peripheral face of a sleeve 47 that is slidable

longitudinally on the spindle 17. The inner end of the abutment plate 46 is formed with an apertured neck 48 that is rotatable on a reduced portion 49 of the sleeve. The neck is maintained in vertical position by a washer 50 in loose abutment therewith and the washer 50 is rigidly anchored to the reduced portion 49 of the sleeve by means of a pin 51.

70 From the foregoing it will be seen that the abutment plate 46 is rotatable on the reduced portion 49 of the sleeve. Anchored to the sleeve 47 and projecting radially therefrom is the shank 52 formed on its outer end with a ball handle 53. The shank 52 is confined within the yoke 42 and is adapted to rest on either one of the legs 43, 44 thereof, when the abutment plate is in certain positions.

75 In the application of the invention, the length of the slice of the article is determined beforehand. The number of gauge fingers 45 will determine the number of different sized slices that can be cut by the slicer. In the form of the invention shown, there are four sized slices that may be cut by a simple manipulation of the abutment handle 53. 80 The length of the slice, of course, will be determined by the distance the abutment plate may be disposed from groove 14.

85 Furthermore, it is to be noticed that the 90 stepped relation of the inner ends of the gauge fingers 45 may be set as desired. The first cut may be maintained by holding the shank 52 against the bight portion of the yoke and since the arcuate blade fits snugly down into the bottom of the depression 13, the length of the slice will be between the groove 14 and the plate 46. The second length of slice is obtained by holding the shank in abutment with the inner end of the first finger of the series 45.

95 The third length slice is obtained by holding the shank in abutment with the inner end of the second of the series of gauge fingers 45. Likewise, the fourth length slice will be obtained by holding the shank 52 against the inner end of the third of the series of gauge fingers 45.

100 It is to be noticed in the present invention, that with the exception of the support most of the parts may be disassembled and cleaned and furthermore, it is to be noticed that all of the parts are very easily assembled and furthermore could be manufactured in great quantities and assembled with great economy.

105 It is to be understood that by describing in detail herein any form, structure, or arrangement, it is not intended to limit the invention beyond the terms of the several claims, or the requirements of the prior art.

110 Having described our invention, what we claim is:

115 1. A slicing machine comprising a base, having a longitudinal depression, a pair of spaced supports on the base, a spindle secured between the supports, a knife rotatable

on the spindle, an abutment plate, means slideable on the spindle for supporting the abutment plate, a plurality of inwardly projecting adjustable gauge fingers secured to one of the supports adapted to engage the last mentioned means for selectively regulating the length of the slice.

2. A slicing machine comprising a base, having a longitudinal depression, a pair of spaced supports on the base, a spindle secured between the supports, a knife rotatable on the spindle, an abutment plate, means slideable on the spindle for supporting the abutment plate, a plurality of inwardly projecting adjustable gauge fingers secured to one of the supports adapted to engage the last mentioned means for selectively regulating the length of the slice, and a groove in the depression in alinement with the knife blade.

3. A slicing machine comprising a base having a longitudinal depression, a pair of spaced supports on the base, a spindle secured between the supports, a knife rotatable on the spindle, an abutment plate, means slideable on the spindle for supporting the abutment plate, a plurality of inwardly projecting adjustable gauge fingers secured to one of the supports adapted to engage the last mentioned means for selectively regulating the length of the slice, and a groove in the depression in alinement with the knife blade, said means including a sleeve having a reduced end and said abutment plate rotatable on the reduced end.

4. A slicing machine comprising a base having a longitudinal depression, a pair of spaced supports on the base, a spindle secured between the supports, a knife rotatable on the spindle, an abutment plate, means slideable on the spindle for supporting the abutment plate, a plurality of inwardly projecting adjustable gauge fingers secured to one of the supports adapted to engage the last mentioned means for selectively regulating the length of the slice, and a groove in the depression in alinement with the knife blade, said means including a sleeve having a reduced end and said abutment plate rotatable on the reduced end, and said groove being arcuate and co-extensive with the base.

5. A slicing machine comprising a base having a longitudinal depression, a pair of spaced supports on the base, a spindle secured between the supports, a knife rotatable on the spindle, an abutment plate, means slideable on the spindle for supporting the abutment plate, a plurality of inwardly projecting adjustable gauge fingers secured to one of the supports adapted to engage the last mentioned means for selectively regulating the length of the slice, and a groove in the depression in alinement with the knife blade, said means including a sleeve having a reduced end and said abutment plate rotatable on the reduced end, and said depression being

arcuate and co-extensive with the base, and spring means disposed about the spindle to normally urge the knife blade out of the depression.

6. A slicing machine comprising a base for supporting the article being sliced, a knife rockably connected with the base, an abutment plate movably mounted on the base, and a plurality of gage fingers connected with the base to limit the movement of the abutment plate for selectively regulating the length of the slice.

7. A slicing machine comprising a base for supporting the article being sliced, a spindle mounted on the base, a knife rockable on the spindle, an abutment plate movably mounted on the spindle, and a plurality of gage fingers associated with the base to limit the movement of the abutment plate for selectively regulating the length of the slice.

8. A slicing machine comprising a base for supporting the article being sliced, a knife, means for rockably connecting the knife with the base, an abutment plate, means connected with the base for moving the abutment plate with respect to the rocking axis of the knife, said last mentioned means being rockable, and gauge means associated with the base and engageable with said second mentioned means at different points on the rocking axis of the second mentioned means for selectively regulating the length of the slice.

In testimony whereof we affix our signatures.
